(57) **CLAIM**

The ornamental design for a media playback device, as shown and described.

DESCRIPTION

FIG. 1 is a front elevation view of a media playback device of the present invention.

FIG. 2 is rear elevation view of FIG. 1.

FIG. 3 is a first side view of FIG. 1.

FIG. 4 is a second side view of FIG. 1.

FIG. 5 is a top plan view of FIG. 1.

FIG. 6 is a bottom plan view of FIG. 1; and,

FIG. 7 is a perspective view of FIG. 1.

The dot-dash broken lines immediately adjacent to the claimed areas in the views represent the boundaries of the design and form no part thereof.

The broken lines in the figures illustrate the portions of the design that form no part of the claimed design

None of the broken lines form any part of the claimed design.
